WELDING ROD BOX

Joseph M. Brinker, Baltimore, Md., assignor of
one-half to Michael Podgurski, Baltimore, Md.

Application May 17, 1943, Serial No. 487,369

5 Claims.

(CL 206—16)

This invention relates to boxes, and more particularly to supply boxes to be used by workman who must have their hands free in order to perform their specific task and who continuously move from place to place as the work progresses.

In modern shipbuilding practice, substantially all of the parts of the boat are assembled by means of welded joints. This necessitates a vast number of welders scattered over the ship and upon scaffolding erected along the sides of the hull. These men must clamber up and down the scaffold and carry with them their welding tools and a supply of rods of welding metal.

The rod is used until just a short stub several inches in length is left that is too short for the welder to use. These butts represent a substantial amount of metal in the aggregate, and may be melted down to form new rods if saved. To drop them on the deck or scaffold for future collection presents a hazard to the workmen, as the rods are round and will roll if stepped upon and may cause serious injury.

The object of the present invention is to provide a box which can be conveniently carried by a welder as he works and in which a supply of welding rods may be kept within easy reach of his hand, the box also serving as a depository for the rod butts.

Another object of the invention is to provide such a box having separate compartments for the new rods and butts, the new rod compartment being so arranged as to permit the rods to feed singly to a point where they may be removed by the welder.

A further object is the provision of openings communicating with the respective compartments, the openings being closed by companion closures which operate simultaneously to uncover or cover the openings, so that when the butt compartment is opened for emptying, the new rod compartment is likewise opened for the insertion of a fresh supply of rods, and when the new rod door is closed the butt compartment is also closed.

Other objects will become apparent from the following description taken in conjunction with the drawing which accompanies and forms a part of this specification, and in which like characters of reference are applied to identical parts throughout.

In the drawing:

Figure 1 is a perspective view of a box incorporating the principles of the present invention;

Figure 2 is a vertical longitudinal sectional view taken on the line 2—2 of Figure 1; and,

Figure 3 is a vertical transverse section taken on the line 3—3 of Figure 1.

Referring to the drawing in detail, the invention consists of a substantially rectangular box 1 having upstanding ears, 2 and 3 provided with slots or openings, 4 to which a carrying strap 5 may be attached. Strap 5 may be sufficiently long to sling the box from the shoulder or it may be provided with a ring 6 by means of which the box may be attached to a snap fastener carried on the belt, or by another strap hung from the shoulder of the welder. Strips 7 of wood or other insulating material are secured to the bottom of the box extending across either end and form supports upon which the box may rest when the welder desires to place it on the deck or scaffold. These strips are of insulating material to prevent the danger of short circuits in the event that the box should contact a naked welding cable.

The interior of the box is divided into two compartments by means of a diagonally positioned partition 8, which is coextensive with the length of the box and extends from the upper rear edge 9 to the lower forward edge 10. This provides a new welding rod compartment 11 forward of, and above, the partition 8, and a butt compartment 12 to the rear of, and below the partition. The inclined partition not only separates the box into two compartments, but by forming a sloping wall for the new rod compartment makes this compartment, in effect, a self-feeding hopper which will keep the rods moving toward the lower forward edge of the box.

The front 13 terminates short of the bottom of the box leaving a narrow slot 14 extending the full width of the box. Slot 14 is slightly greater in height than the diameter of one of the welding rods in order to permit the rods to pass through the slot freely, but not high enough to allow more than one rod to pass through at a time. The bottom of the box is bent downwardly and then curved upwardly at its forward edge to form a trough 15, the trough being positioned outside of the box and at the base of the inclined partition 8 to receive and hold the rods as they pass through the slot 14. The trough, bottom and front of the box, and partition 8 are all cut away midway between the ends of the box at their point of juncture, so that the trough is discontinuous and an arcuate opening 16 is provided to permit the gloved hand of the welder to readily grasp and remove the rod which has

dropped down into the trough. As the rod is removed another rod will pass through the slot and fall into the trough. Therefore, as long as a supply of rods remains in the box, a rod will always be lying in the trough ready for the welder.

The upper central portion of the back wall is pressed outward beyond the top to provide an open inclined chute 17 communicating with the butt compartment 12. The short, stub or butt ends of the welding rods may be dropped into the chute 17 and will fall into the butt compartment 12 where they will be carried until such time as it is desired to empty the box.

At one end the box is provided with two openings 18 and 19 located on opposite sides of the partition 8, the opening 18 giving access to the new rod compartment 11, and the opening 19 communicating with the butt compartment 12. A closure member 20 is pivoted to the end of the box, as at 21, midway between the openings. On either side of the pivotal point 21 the closure member is enlarged, forming disk-like members 22 and 23, the member 22 covering and closing the opening 18, and the member 23 covering the opening 19. The closure may be swung about its pivot 21 to uncover both of the openings so that the compartment 12 may be emptied of the accumulated butts, and a fresh supply of new welding rods may be put into the compartment 11. When the new rods are put into the compartment they will gravitate down into proper position and one rod will pass through the opening to lie in the trough ready for use.

Although a preferred and practical embodiment of the invention has been described in the above and shown on the accompanying drawing, it will be understood to those skilled in the art to which the invention appertains that many changes may be made from the precise structure shown without departing from the spirit of the invention as defined in the appended claims.

What I claim is:

1. In a box for holding a supply of welding rods, an inclined partition within said box forming with the upper part of said box a hopper for welding rods and with the lower portion of said box a compartment for used butts of said rods, the front of said box having an elongated slot

near its lower edge and adjacent to the lower end of said partition, a trough outside the box and adjacent said slot to receive and hold a single welding rod, one end of said box having companion openings communicating respectively with the hopper and said butt compartment, and a closure member adapted to simultaneously cover and uncover both said openings.

2. In a box for holding a supply of welding rods, an inclined partition within said box forming with the upper part of said box a hopper for welding rods and with the lower portion of said box a compartment for used butts of said rods, a chute opening in the plane of the top of said box providing an entry to said butt compartment, the front of said box having an elongated slot near its lower edge and adjacent the lower end of said partition, a trough outside the box and adjacent said slot to receive and hold a single welding rod, one end of said box having companion openings communicating respectively with the hopper and said butt compartment and a closure member adapted to simultaneously cover and uncover both of said openings.

3. In a device as claimed in claim 2, said trough having an intermediate cut away portion forming a fingerhold to permit grasping the rod in said trough.

4. In a device as claimed in claim 2, said trough having an intermediate cut away portion forming a fingerhold to permit grasping the rod in said trough, and a strap secured to said box by means of which the said box may be carried.

5. Box for holding a supply of welding rods having an interior inclined partition forming with the upper part of said box a hopper for welding rods and with a lower portion of said box a compartment for used butts of said rods, the front of said box having an elongated slot near its lower edge adjacent the lower end of said partition, a trough outside the box and adjacent said slot to receive and hold a single welding rod discharged from said hopper, said hopper and said compartment opening endwise at one end of said box and a closure member adapted to commonly cover and uncover both said openings.

JOSEPH M. BRINKER.
